UNITED STATES PATENT OFFICE

120,974

DESIGN FOR A HUB TOOL

James A. Harvey, Roanoke, Va.

Application April 2, 1940, Serial No. 91,418

Term of patent 14 years

To all whom it may concern:

Be it known that I, James A. Harvey, a citizen of the United States, residing at Roanoke, in the county of Roanoke and Commonwealth of Virginia, have invented a new, original, and ornamental Design for a Hub Tool, of which the following is a specification, reference being had to the accompanying drawing, forming a part thereof.

Fig. 1 is an elevational view of one side of a hub tool, showing my new design;

Fig. 2 is an edge elevation thereof;
Fig. 3 is an elevational view, showing the opposite side; and

Fig. 4 is a horizontal sectional view, taken on the line 4—4 of Fig. 1.

I claim:

The ornamental design for a hub tool, as shown.

JAMES A. HARVEY.
